MACHINE FOR WAX COATING COMESTIBLES

Robert N. Maynard, Gasport, N. Y., assignor, by mesne assignments, to S. C. Johnson & Son, Inc., Racine, Wis., a corporation of Wisconsin

Application February 14, 1955, Serial No. 487,762

1 Claim. (Cl. 118—18)

This invention relates to an apparatus for cleaning comestibles and coating the same with wax. The use of wax as a means of affording a protective film for fruits has long been commercially acknowledged. The benefits of such treatment include the retarding of shrinkage and a material enhancement of appearance.

It is an object of this invention to provide an apparatus for cleaning produce and applying wax thereto. Another object of the invention is to provide for metered drip dispensing of either hot or cold liquid wax to achieve a uniform coating of produce. A further object of this invention is to provide a liquid wax dispenser having a plurality of spaced apart metering stations which are actuated in unison and which may be adjusted for drip control either individually or simultaneously.

An additional object of the invention is to provide a metering station for liquid wax dispensing in drop form having a reciprocating drip rod which extends in spaced relation through and beyond a dispensing orifice, whereby said drip rod functions as a clean-out for said orifice. It is a further object of this invention to provide reciprocating rods which function as valves, cutting off the flow of wax on each downward stroke. Finally, it is an object of this invention to provide means for actuating said rods which will maintain them to a valve-closed position when the apparatus is not in operation.

Still further objects and the entire scope of applicability of the present invention will become apparent from the detailed description given hereinafter; it should be understood, however, that the detailed description and specific example is given by way of illustration only and, while indicating preferred embodiment of the invention, is not given by way of limitation, since various changes and modifications within the spirit and scope of the invention will become apparent to those skilled in the art from this description.

For a more complete understanding of the nature and scope of this invention, reference is had to the drawings, specification, and appended claim. Throughout the various figures of the drawings and the description in the specification, like reference numerals refer to similar parts.

Figure 1 is a perspective view of the apparatus according to the invention;

Figure 2 is a fragmentary somewhat enlarged side elevational view of the upper part of the apparatus as viewed from the opposite side of Figure 1;

Figure 3 is a cross-sectional view of Figure 2 except for the wax dispenser;

Figure 4 is an enlarged sectional view along line 4—4 of Figure 3 showing the dispenser according to this invention;

Figure 5 is a cross-sectional view of the dispenser as viewed along lines 5—5 of Figure 4; and

Figure 6 is an enlarged cross-sectional view of one of the dispensing valves as viewed along line 6—6 of Figure 5.

Turning now to Figure 1, the wax applicator of this invention is generally designated by the numeral 10. It

2

consists of 4 vertical corner posts 11, upper and lower longitudinal side members 12 and 13, upper and lower end members 14 and 15, and suitable diagonal brace members 16. The motor platform 17, supporting electric motor 18, is disposed at one end of the framework between lower longitudinal side members 13.

Situated in the upper portion of the framework is the wax dispenser generally designated as 20 and the applicator housing. Reference to Figures 2 and 3 discloses that the applicator housing contains a plurality of parallel rotary brushes 21. Because they are supported by the inclined side member 22, these brushes form an inclined table. Bearings (not shown) for holding the shafts 26 of the brushes may be attached to the inclined members by means such as bolts 23. Produce 24 is carried by the rotation of the table of brushes 21 up the incline thereof as indicated by the arrow in Figure 3. Each of the brushes 21 is caused to rotate by a pulley 25 which is affixed to each end of the brush shaft 26.

20 The drive from the motor 18 is to a counter shaft 27 mounted in pillow block bearings 28 attached to diagonal brace members 29. On the counter shaft 27 is mounted the relatively large drive pulley 30 and the smaller end driven pulleys 31. Attached to motor 18 is a small drive pulley 19 connected by V-belt 32 to counter shaft drive pulley 30. A pair of idler pulleys 33 and 34 supported respectively on brackets 35 and 36 serve to guide the drive belts 37 which pass over counter shaft driven pulleys 31 and the brush pulleys 25 rotating the latter counter-clockwise as shown in Figures 2 and 3. The brackets 35 are formed with a plurality of apertures 38 which receive securing bolts to adjustably position the same on diagonal members 29, thus permitting variation of the tension on belts 37.

35 The lower-most brush shaft 26 drives an additional pulley (not shown) which engages drive belt 39 to drive pulley 40, both shown in Figure 1. Pulley 40 is affixed to the shaft 42 of applicator brush 41. Shaft 42 is supported by bearings 43 which are secured to the intermediate vertical side members 44, best seen in Figures 1 and 2. Figure 2 discloses that the opposite end of applicator brush shaft 42 has pulley 45 mounted thereon for driving vacuum pump drive shaft 48 through belt 46 and pulley 47. Shaft 48 is supported by bearings 49 on upper side members 12 of the framework. On the end of shaft 48, opposite pulley 47, is mounted a wheel 50 which has crank pin 51 attached thereto for reciprocating rod 52 of the vacuum pump 53. The pump 53 is pivotally mounted at its lower end by a pivot pin 54 to side member 22.

The comestibles to be treated are admitted at the lower end of the inclined table of brushes on chute board 55 and are carried from the upper end of the brush table by discharge chute 56. The table of brushes 21 and the applicator brush 41 are in a housing which consists of side panels 57, end panels 58, top panels 59 and 60, and an inclined bottom panel 61. The entrance and discharge chutes each extend through an opening in the respective end panel, the latter being provided with curtains 62 and 63 to prevent the accidental discharge of wax into the area surrounding the machine.

The liquid wax dispenser, generally indicated at 20, is shown in detail in Figures 4 and 5. It includes an elongated tank 64 which has a vertical side wall 65 and a relatively narrow horizontal bottom 66. Superimposed upon the vertical side wall is bracket 67, best seen in Figure 5, which consists of a horizontal shelf portion 68 and a vertical leg 69, the latter being secured by any suitable means, as bolts 70, to said vertical wall. Bracket 67 is disposed at approximately the center of the length of wall 65 and serves as a support for a vacuum diaphragm actuator 71. Front panel 72 of tank 64 slopes

inwardly from the top of the tank while the ends 73 and 74 are vertical. A cover 75 is hinged at 76 to the top of the inclined front wall 72. As seen in Figures 1 and 2, the tank is attached to the framework of the apparatus by brackets 77 which connect the end walls to side frame members 12. The tank 64 is further secured to the frame through wall 65, which is attached to brace member 78, the latter spanning side members 12. As shown in Figure 3, tank 64 is positioned so that it will extend downwardly through the top panel 60 of the housing with tank bottom 66 positioned in a spaced relationship over the wax applicator brush 41.

The vacuum actuator 71 is connected by fittings generally indicated at 79 to a tube 80 which leads to the lower end of vacuum pump 53, as shown in Figure 1.

Bottom panel 66 of the dispensing tank 64 contains a plurality of aligned and spaced apertures 81 which are threaded to receive orifice fittings 82. A suitable drain valve, such as that shown at 83 is also attached to the bottom panel. As is best seen in Figure 6, each orifice fitting 82 has a vertically disposed opening 84 therethrough. The upper portion of this opening consists of a tapered portion 85 which converges from top to bottom thereof, and the lower extremity of which is delineated by throat portion 86. Throat portion 86 located about midway the length of opening 84, communicates with a lower aperture portion 87 which diverges slightly from top to bottom.

Disposed in the vertical opening 84 is a reciprocable valve rod 88 which has a threaded portion 89 at its upper extremity. The threaded portion 89 extends through a bight portion 98 of a U-shaped valve rod mounting bar 97. A threaded rod 99 supports the valve rod mounting bar 97, being adjustably secured by nuts 100 and 101 to the latter, at the mid point of the bight portion thereof. The upper end of rod 99 is attached by means of pin 102 to the lower end of a depending rod 103. Rod 103 extends upwardly through shelf 68 to the diaphragm (not shown) of the vacuum actuator 71. Valve rod 88 is attached to the mounting bar 97 by means of a nut 90 which engages the threaded portion of the valve rod. Each rod is biased from the bar 97 by a compression spring 91, the lower end of which is supported by a washer 92 and pin 93.

The lower end of the valve rod 88, best seen in Figure 6, consists of two cylindrical portions 94 and 96 whose diameters are unequal and less than the upper portion of the rod. Between the two reduced cylindrical portions is a tapered portion 95 which converges from top to bottom and which is tapered to a greater degree than the surrounding tapered portion 85 of the orifice fitting 82. The smaller cylindrical portion 96 of the valve rod has a diameter which is less than that of throat 86 of the orifice fitting. It also should be sufficiently long to extend substantially below the orifice fitting when rod 88 is in its cut-off position, i. e., with tapers 85 and 95 in engagement. In this cut-off position, an annular wedge-shaped space is formed between tapered portions 85 and 95 and the protrusion of cylindrical portion 96 insures the complete cleanout of wax from within fitting 82. Thus, in operation, when a vacuum is produced in actuator 71, mounting bar 97 is raised together with each valve rod 88, and each orifice fitting 82 is opened. When there is no vacuum present in actuator 71, mounting bar 97, valve rods 88, and associated mechanism are pulled downwardly by gravity until each rod 88 reaches its cut-off position with tapers 85 and 95 in engagement. In this manner, closure of the orifice fittings 82 is insured when the metering apparatus of this invention is shut down, as it occurs automatically when pump 53 is stopped and a vacuum is no longer produced in actuator 71.

Each leg of the U-shaped valve rod mounting bar 97 is guided, on one side by the vertical wall 65 of the tank, and on the other side, by a roller 104 which is mounted on each of the walls 73 and 74 by means of pin 105.

As seen in Figure 4, the upward movement of the valve rod mounting bar 97 is limited by an assembly which is attached to wall 65 at either end of the tank by screws 106. This assembly consists of lug 107 which has a threaded aperture extending vertically therethrough for receiving cap screw 108. Spring 109 is compressed between lug 107 and the head of cap screw 108 in order to prevent the accidental tightening of the screw. By adjusting each of the cap screws 108, the upward movement of the mounting bar 97 may be varied resulting in the adjustment of the size of the openings at all dispensing orifices in unison. Thus, if more drops of liquid wax per unit of time are desired to be dispensed, screws 108 are backed off to permit the valve rod mounting bar 97 to move further upward on each suction stroke of the piston rod 52 of vacuum pump 53. On the other hand, the relative position of valve rods 88 with respect to rod 99 may be adjusted in two different ways. The entire assembly comprised of bar 97 and rods 88 may be positioned on rod 99 by means of nuts 100 and 101, or each rod 88 may be individually positioned with respect to bar 97 by means of nut 90 associated with each rod. Spring 91 permits a yieldable seating of each valve rod in orifice fitting 82, compensating for irregularities between the different valve rods and orifice fittings so as to permit each orifice fitting to be tightly closed when no vacuum is present in actuator 71.

Dispenser 20 will meter either a hot or a cold wax composition. In the event that a hot wax is desired, a heating element 110 is provided together with thermostat rod 111 in the bottom of tank 64. Heating element 110 and thermostat rod 111 are secured to end wall 73 of the tank by means of fittings 112 and 113 respectively. After passing through terminal box 114, the leads from the heating element are connected to a control box 115 permitting adjustment of the temperature by means of a dial 116. Temperature control box 115 is then connected to a suitable source of power by cable 117.

The wax applicator brush 41 is generally cylindrical and extends the full width of the dispensing tank beneath the line of orifice fittings 82. Brush 41 is relatively large and fluffy as compared with the brushes 21 which make up the brush table. In operation, comestibles 24, such as apples, are brought into the machine over chute 55 where they are cleaned by the brushes up-stream from applicator brush 41. The rotation of the table brushes 21 carries the apples into contact with applicator brush 41 which is saturated with wax metered from dispenser 20. Brush 41 and the table brush immediately therebeneath cooperate to apply a coating of wax to each apple which continues to be carried up the inclined table of brushes because of their rotation. Further tumbling by brushes 21 produces an even distribution of the wax over each of the apples which are then discharged by chute 56.

The dispenser 20, according to this invention, is especially efficient in dispensing liquid wax in metered drops. Each of the valve rods 88 is so constructed and mounted that it is individually adjustable at all times to ensure seating on the tapered portion of orifice 84. At the same time, the valve rod mounting bar 97 may be adjusted to simultaneously control the extent of reciprocation of all valve rods by adjusting nuts 100 and 101 on actuator rod 99 or by changing the setting of cap screws 108.

The timing of the actuator 71 is based on the reciprocating vacuum pump 53 which is operated simultaneously with the operation of the motor 18 and the rest of the machine. Furthermore, it should be appreciated that the valve rods are reciprocated in such a manner that they come to rest in a valve-closed position when the apparatus is shut off.

The cleaning and waxing apparatus is simple in construction, yet is very efficient in operation. The co-operating wax dispenser with its metering control of drops of liquid wax and its automatically seated valve

rods affords a constant and uniform supply of liquid wax for the applicator brush of the machine.

I claim:

An apparatus for applying a wax-coating to comestibles, comprising in combination a table of rotatable cylindrical brushes for conveying and rotating comestibles deposited thereon; rotary applicator means disposed above said table of brushes for coating the comestibles carried by the latter; liquid dispensing means including a fluid reservoir, a plurality of discharge orifices in said reservoir positioned over said applicator means each having a valve seat therein, a plurality of reciprocal valve rods positioned vertically above said valve seats each having an annular tapered portion thereon for engagement with its respective valve seat, each of said valve rods having a portion thereof extending beyond its annular tapered portion of sufficient length so that said extended portions protrude at all times downwardly through each of said orifices, a central valve rod control bar for withdrawing simultaneously said tapered portions of said valve rods from engagement with their respective valve seats, adjustable means on said valve rod control bar for each of said valve rods for limiting said valve rods downward movement with respect to said control bar, a helical spring circumscribing each of said valve rods positioned at one end against said control bar and at the other end by a stopping means on said valve

rod, an oscillation producing actuator means operatively connected to said valve rod control bar so as to periodically withdraw said valve rods from engagement with said valve seats during operation of said actuator means, said actuator means comprising a pressure responsive diaphragm actuated by a periodic variable pressure generator; and a central driving means for rotating said cylindrical brushes and said applicator means and for supplying energy to said variable pressure generator whereby inactivation of said central driving means stops the rotation of said table of cylindrical brushes and applicator means and simultaneously seats the tapered portion of said valve rods in their respective valve seats to stop the flow of liquid from said reservoir.
